UNITED STATES PATENT OFFICE.

NILS H. ANDERSON, OF MIDDLETOWN, CONNECTICUT, ASSIGNOR TO THE NOISELESS TYPEWRITER COMPANY, OF MIDDLETOWN, CONNECTICUT, A CORPORATION OF CONNECTICUT.

TYPE-WRITING MACHINE.

1,199,227.

Specification of Letters Patent. Patented Sept. 26, 1916.

Application filed August 6, 1913. Serial No. 783,332.

To all whom it may concern:

Be it known that I, NILS H. ANDERSON, a citizen of the United States, residing at Middletown, in the county of Middlesex and 5 State of Connecticut, have invented certain new and useful Improvements in Type-Writing Machines, of which the following is a full, clear, and exact description, such as will enable others skilled in the art to which 10 it appertains to make and use the same.

This invention relates to typewriting machines, and with regard to certain more dominant features thereof, to means adapted to indicate the relative position of the carriage to the common printing point of the 15 various type carriers as well as to the associated coacting parts of such mechanism.

One of the objects of the present invention is to provide a simple and practical 20 form of carriage indicator which will be durable in construction and efficient in action.

Another object is to provide mechanism of 25 the above character which will be silent and reliable in its operation.

Another object is to provide a carriage indicator mechanism of such inexpensive construction as to be commercially practicable and located in such position as to be 30 constantly visible and easily read by the operator.

Other objects will be in part obvious and in part pointed out hereinafter.

The invention accordingly consists in the 35 features of construction, combinations of elements and arrangement of parts which will be exemplified in the construction hereinafter set forth, and the scope of the application of which will be indicated in the following claims.

In the accompanying drawings in which is illustrated one of the various possible embodiments of the several features of the invention, Figure 1 is a plan view showing 45 such parts of a typewriting machine as are necessary to obtain a clear understanding of the present invention; Fig. 2 is a side elevation of the parts shown in Fig. 1; and Fig. 3 is a detailed perspective view of the indicator itself.

Similar reference characters refer to similar parts throughout the different views of the drawings.

Referring now to the drawings in detail,

and more particularly to Fig. 1, there is 55 shown a transverse support 1 adapted to connect the side walls 2 of the frame of the machine. Mounted upon this support 1 is a horizontally disposed U-shaped arm 3 which supports a spring driving drum 4. Within 60 the drum is positioned a spiral spring 5 connected at its outer end to the drum and at its inner end with a central hub 6, to furnish the motive power for driving the carriage, indicated diagrammatically at 7, and 65 ribbon mechanism in the usual manner. This drum 4 is connected with a driving shaft 8 by means of the set screw 9 and is provided at its outer end with a beveled gear 10 meshing with a sheet metal gear 11 70 loose upon a main ribbon spool driving shaft 12. This shaft 12 is provided at each end, only one end being herein shown, with a beveled gear 13 adapted to co-act with a sheet metal beveled gear 14 mounted upon a ribbon spool spindle 15. It will thus be seen that as the shaft 8 is rotated by the drum in one direction motion will be transmitted through the gears 11, 13 and 14 to rotate the ribbon spindle to feed the ribbon from one 80 spool to the other. In order to prevent an unwinding of the ribbon spool when the carriage is returned to normal position, a clutch 16 is interposed between the gear 11 and main driving shaft 12 and is normally 85 held in clutched relation by a spiral spring 17 surrounding the shaft 12 and one end or reduced portion of the clutch. In order to positively hold the shaft against reverse rotation and thus permit the clutch to act, a 90 ratchet 18 is also mounted fast upon the shaft 12, into engagement with which a pawl 20, Fig. 2, is held by means of a spring 21.

Mounted upon the hub of the gear 10 and rotating therewith is a pinion 22 which 95 meshes with another pinion 23 of substantially the same size fixed on one end of a shaft 24 extending fore and aft the machine. This shaft is supported by brackets 25 and 26, near its opposite ends, from any desired fixed 100 part of the frame. At the forward end of the shaft 24 is adjustably mounted an indicator wheel 27 which is graduated to represent the step-by-step movement of the carriage, each step representing one letter 105 space. This scale is preferably divided in the same manner as the paper-finger scale usually positioned upon the carriage above

the platen roller and which it is designed to replace, that is, the scale is divided in 10's, as denoted by the numbers 10, 20, 30, etc., every fifth number being denoted by a 5 heavier line. This scale is visible through a relatively large opening 28 in a housing built in front of the major portion of the front wall of the machine, designed to protect rather than conceal the wheel, as shown 10 more clearly in Fig. 3. This wheel coacts with an adjustable plate 30 carrying a central index or zero point as well as an auxiliary scale to one side thereof. These two indicator scales and relatively large 15 opening in the housing permit of alternative readings thereof. For instance, the scale upon the index wheel 27 may be read directly with respect to the zero point, or the 10's numbers may be read with relation to 20 the number on the auxiliary scale. Thus, as shown in Fig. 3, the carriage occupies the relative position "45" with respect to the type carriers, that is, the number "45" registers with the zero point on the auxiliary 25 scale 30 and also the number "40" registers with the point "5" on the auxiliary scale, the sum of which equals 45. If the carriage is moved forwardly two letter spaces, the mark "40" on the index wheel moves opposite the 30 point "7" on the auxiliary scale; also the point "47" on the indicator wheel 27 will then be opposite the zero point on the auxiliary scale. It will, of course, be understood that this mechanism is provided with 35 various adjusting features in order that the indicator may properly denote the relative position of the carriage. This may be done by moving the auxiliary scale 30 about the central point of support 31, as by loosening 40 the set screw there and rotating it to either the right or left as may be necessary. The indicator wheel 27, mounted upon the end of the shaft 24, may be rotated relatively thereto into the desired adjusted position by 45 loosening nuts 32 and rotating the wheel 27 to the desired adjusted position, after which the nuts 32 are tightened. It will also be noted that the shaft 24 is permitted to have a slight vertical adjustment by moving the 50 bracket 26 relatively to its support by loosening the set screws 33 which pass through slots therein as clearly shown in Fig. 2.

As above explained, the spring driving 55 drum 4 is adapted to drive the carriage 7 by means of a connecting tape 35 in its letter spacing movement. This spring drum, which is preferably made of stamped sheet metal, is provided with a flange 36 for preventing the tape from slipping off the drum on the inside. The back plate 37 of the frame of the machine co-acts with the outer 60 side of the spring drum and prevents the tape from slipping off at that point.

As the operation and method of use of the 65 indicator above described are clear, a reiteration thereof is believed to be unnecessary. It is sufficient to state that the present device is designed to overcome certain objections inherent in present constructions used 70 on visible machines, the principal one being that the paper-finger scale carried by the carriage usually occupies a place above the platen roller, thus more or less obstructing 75 the printed matter, and in order to fully 75 read the page, it is either necessary to rotate the platen roller to feed the paper beyond the scale or move the scale itself. The present device, mounted in the front part of the 80 machine just above the keyboard, is believed to possess all of the advantages of the ordinary scale, but none of its disadvantages, and has besides the merit of bringing the scale to a point on the machine where it is 85 constantly visible for quick reading by the operator. It is also seen that this invention is particularly designed for accomplishing in a simple and practical manner all of the objects and advantages above set forth.

As many changes could be made in the 90 above construction and many apparently 95 widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In a typewriting machine, in combination, carriage driving means, a front plate on the machine having a relatively large opening adjacent the keyboard, a movable scale having a plurality of indices exposed through said opening, said scale being movable with the carriage by said means, and a relatively fixed scale on said front plate adjacent the exposed indices of said movable scale and coacting therewith to indicate the instant travel position of the carriage. 105 110

2. In a typewriting machine, in combination, a spring driving drum, a movable scale positioned in the front part of the machine 115 adapted to be driven by said driving drum, and an adjustable scale coacting with said first-mentioned scale to permit alternative reading of the position of the carriage relative to the printing point. 120

3. In a typewriting machine, in combination, a carriage driving drum positioned at the rear of the machine, a curved scale positioned at the front of the machine, a fixed indicator to co-act with said scale, gearing 125 interposed between the driving drum and said scale for moving the latter relatively to said indicator to indicate the position of

the carriage with respect to the printing point, and means to permit adjustment of one of said scales relatively to the other.

4. In a typewriting machine, in combination, carriage driving means, a front plate, a rotatable scale positioned in front of the major portion of said front plate and adapted to be protected by a minor portion thereof, gearing between said carriage driving means and said scale for moving the latter with the carriage in a predetermined direction, and a relatively fixed indicator scale to co-act with said first-mentioned scale.

5. In a typewriting machine, in combination, carriage driving means, a front plate, a rotatable scale positioned in front of the major portion of said front plate and adapted to be protected thereby, gearing between said carriage driving means and said scale for moving the latter with the carriage, a relatively fixed indicator scale to co-act with said first-mentioned scale, and means to permit adjustment of said indicator scale to register the indices thereon with the indices of said first-mentioned scale.

6. In a typewriting machine, in combination, carriage driving means, a front plate, a rotatable scale positioned in front of the major portion of said front plate and adapted to be protected thereby, gearing between said carriage driving means and said scale adapted to move the scale with the carriage, and an indicator scale adjustably mounted upon the front wall of the machine to co-act with said first-mentioned scale.

7. In a typewriting machine, in combination, driving means, a scale positioned in front of the major portion of the front wall of said machine, connections between said driving means and said scale, a housing for said scale to protect the same and having a relatively large opening therein to expose a large portion of the scale, and means mounted upon the front wall of the machine to co-act with said scale.

8. In a typewriting machine, in combination, driving means, a front wall, a scale positioned in front of the major portion of the front wall, means connecting said driving means and said scale, a housing for said scale to protect the same and having a relatively large opening therein to expose a large portion of the scale, and an adjustably

mounted indicating scale to co-act with said first-mentioned scale to permit of alternative 55 reading.

9. In a typewriting machine, in combination, a movable scale having a plurality of exposed indices remote from the printing line, means to insure corresponding movement of said scale and the carriage, a relatively fixed indicator to coact with said exposed indices for indicating the position of the carriage with respect to the printing point, and means to permit adjustment of 65 said scale relatively to said indicator and to the carriage.

10. In a typewriting machine, in combination, a spring driving drum having a main driving shaft, a gear mounted on said shaft, a driven shaft, a gear mounted thereon meshing with said first-mentioned gear, a rotatable scale at the front end of said driven shaft adapted to be driven from said driving means and at the same rate of rotation, said scale being positioned in front of the major portion of the front plate of the machine, a housing formed by a part of the front wall of the frame of the machine adapted to protect said scale, and a 80 second scale adjustably mounted upon said housing adapted to co-act with said first-mentioned scale.

11. In a typewriting machine, in combination, a spring driving drum having a main driving shaft, a gear mounted on said shaft, a second shaft connected therewith, a rotatable scale at the front end of said second-mentioned shaft, said scale being positioned in front of the major portion of the front plate of the machine, a housing having a relatively large opening formed by the front wall of the frame of the machine adapted to protect said scale, a second scale adjustably mounted upon said housing 95 adapted to co-act with said first-mentioned scale, and means to permit adjustment of both of said scales relatively to each other and to the spring driving drum.

In testimony whereof I affix my signature, 100 in the presence of two witnesses.
